UNITED STATES PATENT OFFICE.

BENJAMIN H. BENNETTS, OF TACOMA, WASHINGTON.

FILTERING AND DECANTING APPARATUS.

1,368,687.

Specification of Letters Patent. Patented Feb. 15, 1921.

Application filed December 2, 1919. Serial No. 341,912.

To all whom it may concern:

Be it known that I, BENJAMIN H. BENNETTS, a citizen of the United States, and resident of the city of Tacoma, county of Pierce, and State of Washington, have invented, certain new and useful Improvements in Filtering and Decanting Apparatus, of which the following is a specification.

10 My invention relates to improvements in filtering and decanting apparatus, and has for its principal object means to provide apparatus for facilitating the filtering or decanting of solutions from one, or simultaneously from a plurality, of beakers, or other receptacles, in a manner that is convenient, efficient, which requires a minimum amount of personal time and attention, and whereby danger to the breakable apparatus and some- 20 times resultant danger to the operator is practically eliminated.

It is also an object of the invention to provide filtering apparatus whereby handling of the receptacles containing the solutions to be filtered, is not required after the beakers are once placed in position within the apparatus, and whereby the sediment or precipitate which may be contained within the beakers is in the least disturbed until such time when it is desired that it be washed into the filters.

A further object of the invention is to provide apparatus of the above character that may be adjusted for the accommodation of beakers and funnels of various sizes, and to provide a control mechanism for the beaker tilting and supporting shelf whereby the solutions may be poured from the beakers into filtering funnels at any desired or required speed or in any quantity needed.

In accomplishing these and other objects of the invention, I have provided the improved details of construction, the preferred forms of which are illustrated in the accompanying drawings, wherein—

Figure 1 is a perspective view of a filtering and decanting apparatus constructed according to the present invention, showing the apparatus in use.

Fig. 2 is a transverse, vertical section of the same.

Fig. 3 is a front view of one end of the apparatus.

Fig. 4 is a detail view, illustrating the means for adjustably and yieldingly supporting the beaker clamping bar.

Referring more in detail to the drawings—

1 designates a supporting shelf whereon a plurality of beakers 2, containing solutions to be filtered, may be placed. This shelf 60 comprises a front portion 1' that is fixed perpendicularly to the base, against which the beakers may be clamped, during a filtering operation, as will presently be described.

Fixed to the outer side of the shelf front 1', 65 at the opposite ends thereof, are hangers 3, each provided with a plurality of downwardly opening notches 4 adapted to receive the outer ends of supporting pins 5 that extend laterally from the upper ends of standards 6 fixed to the ends of a supporting frame 7. The standards 6 are provided with longitudinal slots 6' through which the shank of a clamping bolt 8 is extended to clamp the standard to the end, or leg, 70 75 of the frame 7 at any adjusted position within the limits of the slot.

The shelf is swingingly supported by these hangers 3 and by means of a pair of cables 12 which are fixed at their ends to the under side of the shelf and are wound upon spirally grooved drums 13 fixed on a winding shaft 14 supported revolubly at the upper ends of standards 15 that are also carried by the end members of the supporting frame 7 as is particularly shown in Fig. 1.

The shaft 14 is provided at its ends with winding cranks 16 whereby it may be revolved to swing the shelf upwardly on its mountings to tilt the beakers, that may be mounted thereon, into pouring position. A small ratchet wheel 19 is fixed to the shaft adjacent one end and a pawl 20 is pivotally mounted on a standard 15 to engage therewith to prevent unwinding of the cables from the drums so that the shelf may be retained at any adjusted position.

The standards are each provided with a forwardly directed member 15' which is slotted to slidably receive a clamping screw 21 and a guide pin 22 to hold the standards substantially vertical and at the same time permit them to be adjusted forwardly or rearwardly in accordance with the adjustment 100 105 of the standards 6 or the positioning of the hangers 3 on the supporting pins 5.

Mounted at the front of the frame, in parallel relation with the shelf 1, is a funnel supporting bar 25. This bar is provided 110 with a plurality of downwardly tapering apertures 27, spaced in accordance with the

spacing of the beakers on the shelf 1, through which funnels 28 may be extended; the upper ends of the funnels being in such position as to receive the contents of the beakers 5 and their lower ends being disposed above receiving beakers 30 which catch the filtered solution.

The bar 25 is also adjustably supported by means of arms 32 provided with slots 33 10 for receiving clamping bolts 34 which may be loosened to permit adjustment of the funnel supporting bar to a position to accommodate different sizes of beakers.

The means employed for spacing and retaining the beakers on the shelf 1 during a filtering process consists of a bar 35 bent in a series of corrugations which receive the outer walls of the beakers to space them at regular intervals according to the spacing 20 of the funnels. This bar is yieldingly clamped against the beakers by means of clamping springs 37 which seat against the outer face of the front of the shelf and press outwardly against washers 38, that are fixed 25 at the outer ends of bolts 39 which extend centrally through the springs, slidably through the shelf front, through slots 40 in the bar, and are provided at the inner ends with rings 41 which engages the outer face 30 of the bar.

The bolts 39 are also provided near the ring end with a series of closely spaced lugs 43 which may be moved through the bar slots to engage the outer face of the bar to 35 adjust the same inwardly to hold different sizes of beakers.

Assuming that the apparatus is so constructed, in using the same for filtering purposes, the beakers containing the solution, 40 or solutions to be filtered are first clamped on the shelf 1 while it assumes a position similar to that shown in dotted lines in Fig. 2. The funnels containing the filtering paper, and the receiving beakers, are then 45 placed in receiving position by an adjustment, if necessary, of the bar 35.

The operator then winds the cables 12 on the drums 13 to swing the shelf upwardly on its mounting, so that the beakers will be 50 slightly tilted and some of the solution is poured into the funnels, wherefrom it may filter into the receiving vessels.

If the filtering is slow, the beakers may be retained in this position; being held by 55 the cables which are prevented from unwinding by the pawl which engages the ratchet wheel fixed on the shaft 14, and the operator in the meanwhile may go on about other work.

60 After this first funnel full has been filtered, the operator winds the cables in a little farther to pour more of the solution into the filtering funnels. This performance is repeated as often as necessary or desired, 65 until the beakers are emptied. If sediment

or precipitate remains in the beakers it may then be washed out.

It is apparent that with such an apparatus, there will be no disturbing of the sediment contained within the solutions, as 70 is usual when the beakers are lifted time after time to fill the funnels, and practically all danger of breaking the beakers or of injury to the operator in handling the same, 75 is eliminated.

It is further apparent that the adjustments provided for the different parts of the apparatus will permit the use of receptacles of various sizes and that filtering or decanting is effected in an easy, efficient, safe, 80 and time saving manner.

Having thus described my invention, what I claim as new therein and desire to secure by Letters Patent, is:

1. In a device of the character described, 85 a frame structure comprising a horizontal bar for the support of receiving vessels, a shelf disposed in parallel relation to said bar whereon dispensing receptacles may be removably supported, hangers pivotally and adjustably fixed to the frame and to the shelf to swingingly support the latter, means for actuating the shelf to tilt receptacles that may be supported thereon, to dispense their contents into receiving vessels 90 95 that may be supported by the said bar.

2. In a device of the character described, 100 a frame structure comprising a horizontal bar provided at spaced intervals along its length with openings for receiving and supporting funnels therein, a shelf swingingly supported in parallel relation to the said bar whereon dispensing vessels may be mounted, a spacing and clamping bar 105 mounted upon the shelf to yieldingly retain dispensing vessels that may be placed thereon spaced in accordance with the openings in said bar, means for actuating the shelf to tilt receptacles that may be clamped thereon to dispensing position. 110

3. In a filtering device, a supporting frame, a pivotally suspended shelf comprising a base portion and a front portion perpendicular thereto, a clamping bar for engaging vessels placed on the base to hold them against 115 the front portion, said bar having slots therein, supporting bolts for said bar extended slidably through the said shelf front having holding lugs at spaced intervals thereon projectable through the bar slots, 120 springs secured on the bolts about their inner ends and engaging the shelf front to yieldingly hold said bar in clamping position and means for actuating the shelf to and from dispensing position. 125

4. In a device of the character described, 130 a supporting frame, vertically adjustable standards mounted at the opposite ends of said frame, and having pivot pins in their upper ends, a shelf comprising means where-

by a plurality of dispensing receptacles may be held thereon, hangers extended from said shelf having notches at different points along their length to receive the said pivot pins, and means for swinging the shelf about the pivot points to move the receptacles to dispensing position.

5. In a filtering device of the character described, a supporting frame, a pair of laterally and vertically adjustable standards mounted on said frame, pins extending from the upper ends of said standards, a beaker supporting shelf, suspending hangers fixed to the shelf at its opposite ends and 10 having notches therein to receive said pins, a clamping bar yieldingly mounted on the shelf to removably retain a plurality of dispensing beakers, means for swinging the shelf on its mounting and means for retaining 15 the shelf at an adjusted position.

20 6. In a filtering device of the character described, in combination, a supporting

frame, a beaker supporting shelf, vertically adjustable standards fixed to the ends of said frame, pins extending laterally from 25 said standards, hangers fixed to said shelf at its opposite ends and having notches at different points along its length to pivotally receive said pins to adjust the swing of the shelf, means for functionally retaining a 30 plurality of beakers on said shelf, a pair of standards mounted on the frame and adjustable toward and from the shelf in accordance with the length of swing of the shelf, a shaft revolvably supported by said 35 standards, winding drums on said shaft, cables fixed to said shelf and wound on said drums and means for actuating the shaft to wind the cables on or from said drums for the purpose set forth.

40 Signed at Tacoma, Washington, this 24th day of November 1919.

BENJAMIN H. BENNETTS.
